UNITED STATES PATENT OFFICE.

THOMAS H. CARROLL, OF PHILADELPHIA, PENNSYLVANIA.

LOCKING DEVICE.

1,274,137.

Specification of Letters Patent. Patented July 30, 1918.

Application filed August 21, 1917. Serial No. 187,388.

To all whom it may concern:

Be it known that I, THOMAS H. CARROLL, a citizen of the United States, residing at Philadelphia, in the county of Philadelphia and State of Pennsylvania, have invented 5 new and useful Improvements in Locking Devices, of which the following is a specification.

My invention relates to new and useful 10 improvements in locking devices and has for its object to provide an exceedingly simple and effective device of this character whereby two members may be readily and quickly locked together or unlocked or separated 15 when desired.

Another object of the invention is to provide a locking device particularly adapted to be used at places where the parts may be concealed but which may be readily manipulated when the parts are accessible. 20

A further object of the invention is to provide a locking device for separable supporting members or brackets, such as holders for rolls of goods to be dispensed, as for 25 instance rolls of toilet paper, paper towels, cloth, oil cloth or other goods generally made up into rolls.

With these ends in view, this invention consists in the details of construction and 30 combination of elements hereinafter set forth and then specifically designated by the claims.

In order that those skilled in the art to which this invention appertains may understand 35 how to make and use the same, I will describe its construction in detail referring by numerals to the accompanying drawings forming a part of this application in which—

40 Figure 1, is a side elevation of my improved locking device illustrating its use with a toilet paper roll holder, parts thereof, being shown in section and illustrating a paste board tube in section and partly broken 45 away on which the toilet paper is wound.

Fig. 2, is an end view thereof with the upper portion of one of the side arms broken away.

Fig. 3, is a side elevation thereof with 50 parts shown in section to clearly illustrate the construction.

Fig. 4, is a similar view illustrating the positions of the different parts when the separable member is unlocked.

55 Fig. 5, is the inner end view of one of the barrels.

Fig. 6, is a section of the line 6—6 of the Fig. 5.

Fig. 7, is an end view of the locking bolt or rod. 60

Fig. 8, is a side elevation thereof.

Fig. 9, is an inner end view of the other barrel.

Fig. 10, is a side elevation thereof partly broken away to illustrate the construction 65 and slightly different mode of fastening the spring locking member therein.

Fig. 11, is an end view of the spring locking member, and

Fig. 12, is a section at the line 12—12 of 70 Fig. 11.

In carrying out my invention as here embodied, 2 represents a base plate which is adapted to be attached to an object, such as a wall in any suitable and well known manner and intermediate its ends said base plate is provided with a flange 3 on its two opposite edges to form trackways and at one end of these trackways is inserted a foot 4 of the stationary bracket 5, said foot being 80 fixed to the base plate in any suitable manner as by spot welding. Adjacent the outer end of the bracket 5 and on its inner face is fixed a disk 6 having a central opening 7 which aligns with the hole 8 in the bracket 85 and this disk carries stop means, such as an outwardly projecting lug on lugs 9.

The reference numeral 10 represents a rotatable barrel open at its outer end and adapted to inclose the disk 6 and this outer end is provided with an outwardly projecting flange 11 adapted to engage the inner face of the bracket 5. This barrel carries a tube 12 located in said barrel and attached to its outer end, said tube having a central 90 bore 13 on two different diameters, the larger diameter being at the inner end of the barrel and forms a chamber 14 for a purpose to be hereinafter described.

A number of resilient or spring holding springs 15 are formed integral with the barrel 10 by partially cutting sections of the material of said barrel therefrom and bending the same outward as plainly shown in Fig. 1. 100

The barrel 10 is placed about the disk 6 and the locking pin or rod 16 is then inserted in the central bore 13 of the tube 12 with the reduced end 17 passing through the opening 7 and the hole 8 which is then 110 secured to the bracket 5 in any suitable and well known manner as by heading the end

of said rod as shown in Fig. 3. The rod 16 carries a pin 18 some distance from its end of attachment and this pin coacts with the shoulder 19 formed by the difference in 5 diameters of the central bore 13 and the chamber 14 thereby preventing longitudinal movement of the barrel but permitting the same to rotate upon a locking rod and this barrel further carries a stop lug 20 coacting 10 with the stop means 9 to limit the movements of said barrel, the same being normally forced in one direction by means of the helical spring 21 coiled about the tube 12 and having one end attached to the 15 bracket or the disk 6 carried thereby as the stationary member, the other end being fixed to the barrel as the movable member.

At the opposite or free end, the locking rod 16 is provided with the conical head 22 and on this rod 16 between the pin 18 and the head 22 is slidably mounted a sleeve 24 which acts as a key and the end of said key sleeve which coacts with the head is beveled inward toward its end as at 25, and the extreme end of this sleeve is slightly larger in diameter than the largest portion of the conical head 22. At the other end of the trackways is slidably and detachably inserted the foot 4 of the separable or removable bracket 26 to the outer end of which is fixed another barrel 27 having an exterior flange 28, whereby said barrel may be fastened to the bracket in some suitable and well known manner as by spot welding. 30 The inner end of this barrel is provided with a hole 29 for registration with the locking rod 16 and its key sleeve and in this barrel is mounted the spring locking member 30 plainly shown in Figs. 3, 11 and 12. The 35 locking member 30 consists of a body or disk 31 having a central opening 32 surrounded by an integral riveting flange 33 which is adapted to pass through the hole 29 in the barrel 27 and then turned over or 40 beaded as plainly shown in Fig. 3. From the body 31 projects a pair of oppositely disposed resilient or spring arms 34 converging toward their free or outer ends and these arms are adapted to pass over the conical head 22 of the locking rod and drop behind the larger or base portion of said head to prevent the removal of said locking member from the locking rod as will be obvious.

In Fig. 10, I have shown a slightly different construction of spring locking member in which the riveting flange 33 is dispensed with, and in this form of the device a hollow or tubular rivet 35 is used for fastening the spring locking member within the 45 barrel 27. The rivet is provided with a bead or flange at one end and when the spring locking member is so locked that the hole 32 is in alignment with the hole 29 in the barrel, the ring is inserted from the inner 50 or back side and passed through these holes

and then flanged or beaded on the outside as plainly shown in Fig. 10.

I will describe the working of my improved locking device in conjunction with a toilet paper roll holder in order that the 50 operation may be thoroughly understood. The separable bracket 26 being removed, the roll of paper with its cardboard tube 36 is placed over the barrel 10 where it is gripped by the spring members or fingers 34 thereby 55 attaching the roll of paper to the barrel 10 so that they will rotate together. The separable bracket 26 is then placed in position by inserting the foot 4 in the end of the trackway on the base plate and as the separable bracket 26 is moved to its proper position, the opening 29 in the barrel 27 will register with the locking rod 16 and at the same time the barrel 27 will pass into the other end of the base board tube 36 of the 60 roll of paper.

In positioning the separable bracket 26, the ends of the resilient or spring fingers 34 will pass over the conical head 22 of the locking rod and snap down behind the larger or base portion of said head in the region of the neck 23 thereby securely locking the separable bracket in position, and if any attempt is made to force the separable bracket 26 from the base plate, the 65 spring fingers 34 will be caused to more firmly grip the locking rod 16 because of their angular positions. As the paper is withdrawn from the roll, the barrel 10 will be rotated therewith against the action of the spring 21 which will increase the tension of said spring to such a degree that a portion of the paper will be torn from the roll at the first or second row of perforations or the barrel will come to a stop which will 70 cause the paper to be torn thereby reducing to a minimum the possibility of anyone removing a great amount of the paper and preventing wastefulness. As the roll of paper is securely locked in place, the entire roll 75 cannot be removed at one time and stolen, and as the paper cannot be unwound without a great amount of trouble with its attendant loss of time, it is unlikely that anyone would attempt to remove an entire roll 80 of paper when placed in the holder constructed in accordance with my improvement.

When the entire roll of paper has been 85 used or removed, the cardboard tube 36 may be readily torn from the holder which will give access to the key sleeve 24, then by moving said key sleeve toward the free end or head 22 of the rod 16, the beveled end 90 of said key sleeve will enter between the spring fingers 34 and support them apart beyond the outer circumference of the largest portion of the conical head 22, thereby disengaging said spring fingers from the 95 head of the locking rod and permitting the 100

withdrawal of the separable bracket 26 at which time another roll of paper may be placed on the hole.

Of course, I do not wish to be limited to the exact details of construction as herein shown as these may be varied within the limits of the appended claims without departing from the spirit of my invention.

Having thus fully described my invention 10 what I claim as new and patentable is—

1. A locking device comprising a locking member having resilient, converging fingers, a locking rod having a head, a portion of which is larger than the rod, and means 15 slidable on said rod for moving the fingers apart whereby the locking member may be disengaged from the locking rod.

2. A locking device comprising a locking rod having a head of larger diameter than 20 the rod, a locking member provided with resilient, converging fingers adapted to engage the inner end of the head and means on the rod whereby the fingers may be disengaged from the head.

25 3. A locking device comprising a locking rod having a head of larger diameter than the rod, a locking member provided with resilient, converging fingers adapted to engage the inner end of the head, and a key 30 sleeve slidable on the rod and having a beveled end for coaction with the fingers to move them apart and disengage them from the head.

4. In a locking device, a rod provided with 35 an enlargement, separable means carrying converging fingers to engage the enlargement for locking the rod and separable means together and means on the rod to disengage the fingers from the enlargement 40 whereby the separable means may be unlocked from the rod.

5. In a locking device, a rod provided with an enlargement, separable means carrying converging fingers to engage the enlargement 45 for locking the rod and separable means together and a key sleeve having a beveled end for disengaging the fingers from the enlargement for the purpose stated.

6. In a device of the character stated, a 50 stationary supporting member, a locking rod

having one end attached thereto, a conical head at the other end of the rod, the base or inner end of said head being of greater diameter than the body of the rod, a separable supporting member, locking fingers 55 carried thereby adapted to pass over the head and engage the larger or base portion thereof to lock the supporting members together and means on the rod to disengage the fingers from the head for unlocking the 60 supporting members.

7. In a device of the character stated, a stationary supporting member, a locking rod having one end attached thereto, a conical head at the other end of the rod, the base 65 or inner end of said head being of greater diameter than the body of the rod, a separable supporting member, locking fingers carried thereby adapted to pass over the head and engage the larger or base portion 70 thereof to lock the supporting members together, and a key sleeve having a beveled end slidable on the rod, the smallest portion of the beveled end being slightly larger than the largest portion of the head whereby the 75 fingers may be disengaged from the larger end of the head.

8. In a device of the character stated, a base plate having trackways, a stationary bracket carried thereby at one end thereof, 80 a barrel provided with resilient gripping devices supported by said bracket, a locking rod carried by said bracket and passing through the barrel, a head on the free end of said rod, a separable bracket engaging 85 the trackways for attaching said bracket to the base plate, a barrel supported by the last named bracket and having a hole therein for registration with the locking rod, a locking member within the last named barrel, said 90 locking member having converging fingers for engagement with the rear end of the head and a key sleeve slidable on the rod for disengaging the fingers from the head to permit the removal of the separable 95 bracket.

In testimony whereof, I have hereunto affixed my signature.

THOMAS H. CARROLL.
